SHOE TIP PROTECTOR

Oscar J. Chertok, Brooklyn, N. Y.

Application April 5, 1941, Serial No. 386,974

4 Claims. (Cl. 36—72)

This invention relates generally to the footwear art, and more particularly to tip or front portion shoe protectors.

Among the objects of the present invention lies the provision of a shoe tip protector which is relatively inconspicuous when worn so that the same does not detract from the appearance and style qualities of the shoe.

Another object herein lies in the provision of a shoe tip protector composed of transparent material or other decorative material which finds especial value in connection with shoes of open toe construction.

Another object herein lies in the provision of shoe tip protecting structure which is light in weight, yet of high strength so that not only does the shoe with the protector present a neat appearance, but the shoe is comfortable and not made clumsy by unnecessary weight, yet the protector prevents the shoe from being injured thereunder, and also acts to protect the wearer's foot should any heavy object fall upon the shoe.

Another object herein lies in the provision of shoe tip protecting structure which is readily fabricated in large quantities at low cost so that the same may have a consequent wide use and distribution.

A still further object herein lies in the provision of shoe tip protecting structure which is readily detachably engageable with the shoe, requiring no special tools or skill for this purpose. In accordance with the present novel construction, the shoe tip protector when in place does not damage the shoe in any conspicuous or vital portions thereof.

A feature of the present invention lies in the fact that when the shoe protector is in place upon the shoe, the protector is securely held thereat against movement in many directions so that accidental displacement thereof is extremely remote.

These objects and other incidental ends and advantages will more fully appear in the progress of this disclosure and be pointed out in the appended claims.

In the drawings constituting a material part hereof, similar reference characters designate corresponding parts throughout the several views in which:

Figure 1 is a front elevational view of a shoe having associated therewith a first embodiment of the invention.

Figure 2 is a fragmentary enlarged vertical sectional view, constituting a medial section of the forward portion of Figure 1.

Figure 3 is a fragmentary enlarged view in perspective showing in detail two of the sole edge engaging prongs and adjacent parts.

Figure 4 is an enlarged top plan view of the protector shown in Figure 1.

Figure 5 is a reduced view in perspective showing principally the sole portion of the shoe of Figure 1, with the tip protector in place.

Figure 6 is a fragmentary view in perspective, similar to Figure 1, but taken from a higher viewpoint.

Figure 7 is a perspective view of a second embodiment of the invention, in place upon a shoe.

Figure 8 is an enlarged fragmentary sectional view showing the penetration of one of the prongs into the sole.

Figure 9 is a view in perspective showing a pair of woman's open toe slippers, as worn; the right hand slipper having a third embodiment of the invention in the form of a shoe tip protector, in place.

Figure 10 is an enlarged side elevational view of the protector shown in Figure 9, as removed from the slipper.

Figure 11 is an elevational view as seen from the left side of Figure 10 showing the inside of the protector.

Figure 12 is a fragmentary, horizontal sectional view as seen from the plane 12—12 on Figure 11, showing the protector in place upon an open toe slipper.

Figure 13 is a view in perspective showing a toe dancing slipper as worn, with a fourth embodiment of the invention, in place, in the form of a slipper tip protector.

Figure 14 is an enlarged rear elevational view of the slipper shown in Figure 13.

Figure 15 is a sectional view as seen from the plane 15—15 on Figure 14.

Turning now to the first embodiment of the invention illustrated in Figures 1 to 6 and Figure 8 inclusive, the shoe tip protector is generally indicated by numeral 10. The protector 10 is of irregular configuration and the shape thereof is best seen in the several figures of the drawings. The protector 10 includes a shoe tip covering portion 11; a welt engaging rib 12; a sole top engaging flange 13; a sole periphery engaging vertical rim 14; and a sole bottom engaging lip 15.

The protector 10 is preferably fabricated of a stiff material having some resiliency. An example of such material is sheet steel. When made from sheet steel, the protector 10 may be manu-

factured in one piece by suitable blanking and forming operations.

The tip covering portion 11 is generally of convex shape, but the configuration thereof is primarily determined by the external configuration of the shoe tip 16. The upper rear edge 18 of the portion 11 may extend rearwardly on the shoe any suitable distance, and the rearward extension of said edge is determined by the amount of the front upper portion of the shoe which it is desired to protect. The inner surface of the toe or tip covering portion 11 is provided with a lining 19 which may be composed of any suitable cushion material, as for example, felt or flannel. The lining 19 may be secured to the inner surface of the portion 11 in any suitable manner, as for example, by means of an adhesive (not shown). The lower forward and outer edge of the portion 11 is disposed inwardly (rearwardly and inwardly of the shoe when placed thereon) and forms in part the welt engaging rib 12. From the welt engaging rib 12, the material of which the protector 10 is composed extends radially outwardly in a horizontal plane to form the flange 13. The convergence or juncture formed by the lower front part of the tip covering portion 11 and the rear part of the sole top engaging flange 13 form an acute angle with relation to each other.

The outer edge portion of the sole top engaging flange 13 forms a right angle with relation to the vertical rim 14 which engages the periphery of the sole. The rim 14 is preferably coextensive with the edge 18, though where desired, said rim may extend rearwardly along the edge of the sole 20, to some point beyond the edge 18. The forward portion of the lower edge 21 has extending rearwardly therefrom, and preferably at right angles thereto, the bottom engaging lip 15. The rear edge 22 of the lip 15 is preferably rounded as best seen in Figure 4. The inner opposed surfaces of the flange 13 and the lip 15 are preferably parallel and are spaced from each other a distance equal to or slightly greater than the thickness of the sole 20.

The rear portions of the rim 14 are provided with sole engaging prongs 23 to 26 inclusive. These prongs have a triangle shaped point portion, generally indicated by numeral 27, and a rectangular portion, generally indicated by numeral 28, and have the point thereof, when it is blanked from the sole periphery engaging vertical rim 14, facing rearwardly of the shoe 17, and the protector 10. These prongs are formed by making a series of incisions 29, the rear portions of which are V-shaped, while the forward portions of which have parallel sides, horizontally disposed with relation to the protector 10. After the blanking operation, the prongs are bent as best seen in Figures 3 and 4, so that the entire prong lies outwardly of the rim 14, or so that at least, the innermost tips of the points 27 do not extend inwardly of the inner surface of the rim 14. The rim 14 is composed of relatively stiff material of a low order of resiliency so that the prongs may be pushed into the edge of the sole 20 by pressure upon the portion 28, and when so driven into the sole edge, will maintain themselves in their altered, inwardly displaced position. The prongs may be forced inwardly by pressure in a suitable vise or press; or they may be driven in by hammering with a light hammer upon the rectangular portions 28. It may thus be seen that the prongs rotate substantially as a unit about the vertical axes 33 and to that

end, the point portions 27 may, if desired, be given a slightly curved configuration so that the said point portions lie along an arc traced by the outer edge of the rectangular portions 28 when the same are moved in toward the sole edge.

The outer surface of the protector may be treated in such manner as to take on an appearance harmonious with the shoe with which the protector is to be used. Examples of such finishes are bright plating, colored enamel, or certain chemical finishes such as gun-metalling. The brighter finishes are more suited to children's shoes while the more subdued finishes are more adapted for adults' shoes.

The sole top engaging flange is preferably of uniform width so that the same may properly overlay the upper portion of the exposed sole edge.

Operation

The operation of the first embodiment of the device is substantially as follows:

The protector 10 is held in a position corresponding to the one it will occupy when fully seated upon the shoe and with the lower surface of the lining 19 resting upon the outer surface of the shoe tip 16, the entire device is moved rearwardly upon the shoe. As the device is pushed to the rear, the rim 14 will be guided in position as the flange 13 slides over the upper surface of the sole edge. Since the prongs 23 to 26 inclusive are positioned outwardly of the inner surface of the rim 14, they do not contact the outer surface of the edge of the sole 20 until they are pressed inwardly as described above. The device is pushed into this fully seated position so that the portion 35 (see Figure 2) contacts the outer surface of the sole 20 at the front central portion thereof. After the prongs have been properly driven into the sole edge, the protector becomes, for practical purposes, an integral part of the shoe. Movement of the protector 10 downwardly of the shoe is prevented by the under surface (really the lining 19) of the tip covering portion 11 and the under surface of the flange 13 abutting the shoe and preventing such movement. Upward movement of the device is prevented by the rib 12 and the lip 15 abutting the adjacent parts. Rearward movement is prevented by the portion 35 abutting the forward central portion of the front edge of the sole 20 as well as other parts abutting the shoe. Forward movement of the protector 10 relative to the shoe is prevented by the prongs 23 and 26 inclusive penetrating into the edge of the sole 20.

Where it is desired to remove the protector, it becomes a simple matter to insert a thin knife blade or other pointed instrument between the inner surface of the rectangular portions 28 and the edge of the sole 20, a simple prying movement will then return the prongs to the position shown in Figures 3 and 4, so that the whole protector 10 may be slid forwardly off of the shoe 17.

When desired, in order to increase the stiffness of the bends 31, the portions 27 and 28 thereto adjoining, may be given a slight camber or rib (not shown), said camber or rib being arcuate when seen in vertical section, about horizontal axes.

Turning now to the second embodiment of the invention shown in Figure 7, parts corresponding to the first embodiment are given singly primed reference characters for the purpose of avoiding needless repetition.

The principal difference existing between the

first embodiment and the second embodiment lies in the fact that the tip covering portion 111 is provided with a plurality of perforations indicated generally by numeral 37 and stitch markings indicated generally by numeral 38; and the sole top engaging flange 113 is provided with a plurality of stitch markings 39 and stitcher knife marks 40.

Another difference between the first and second embodiments lies in the fact that the edge 18 is irregularly shaped to conform to the shape of the shoe tip which lies directly therebelow. It is thus seen that the protector 10' may be so shaped and decorated that when in place, it is difficult to notice that the shoe 17 carries tip protecting means thereon; yet all of the usefulness and advantages of the present tip protecting construction are retained.

Turning now to the third embodiment of the invention illustrated in Figures 9 to 12 inclusive, the shoe tip protector, generally indicated by numeral 110, includes a tip covering portion 111, a welt engaging rib 112, a sole top engaging flange 113, a sole periphery engaging vertical rim 114, and a sole bottom engaging lip 115.

As in the case of the first embodiment, the general external configuration of the shoe tip protector 110 is best seen in the drawings and is adapted to conform to the configuration of the shoe or slipper 117. This embodiment is particularly adapted for use with women's shoes or shoes of the slipper type in which the sole 120 is relatively thin. The slippers 117 include a tip portion 116 having a toe opening 143. The inner lower portion of the tip covering portion 111, slightly above the welt engaging rib 112, is provided with a clasp member 123. The clasp member 123 is preferably composed of resilient material and is preferably of an elongated bar shape, normally rectilinear. When the protector is composed of metal, the clasp member 123 may be composed of a springy material such as spring steel or brass, and the same may be welded or soldered to the inner surface of the tip covering portion 111 at the area indicated by numeral 124. The length of the clasp member 123 is greater than the total width of the toe opening 143, and I have found it preferable to make the end 125 longer than the end 126, the end 125 being disposed at the left or inner edge of the shoe as related to the wearer. The protector 110 may then be put in place by passing the end 125 inside of the shoe at the same time the portion 127 of the protector 110 is placed on the tip portion 116. The end 126 is then flexed manually and placed into the opening 143 at the same time moving the portion 128 rearwardly into place. The protector 110 is then maintained in operative position by the clamping or clasping portion of the member 123, which, since it is in a previously distorted position offers a constant pressure outwardly toward the inner surface of the portions 127 and 128.

As in the case of the first embodiment, the member 110 may be given any suitable exterior decorative treatment, and if desired, the same may be lined with material adapted to protect the shoe thereunder.

Since the protector shown in the third embodiment may find its principal usefulness as an emergency measure to cover the open toes 143 of the shoes 117, I have found it desirable to fabricate the protector 110 of transparent plastic materials such as cellulose acetate, methyl methacrylate, or certain vinyl compounds sold

under the trade name of Vinylite. Obviously, where such materials are used, suitable means may be used to connect the clasp member 123 to the tip covering portion 111 at the area 128, as for example, in the case of cellulose acetate, suitable cement may be used. After the device 110 is in place, movement upwardly is prevented by the portion 118 (sole bottom engaging lip); downwardly by the portion 111; rearwardly by the device itself; and forwardly by the action of the clasp member 123.

Turning now to the fourth embodiment of the invention, a protector 210 is shown, especially adapted for use with a toe dancing slipper 217. In a toe dancing slipper, the sole 220 is relatively thin, so as to prevent engagement of the sole at the peripheral edges thereof by the prongs 223 to 226 inclusive. In this embodiment, therefore, I prefer to have the prongs engage the bottom surface of the sole 220.

The shoe tip protector 210 includes a tip covering portion 211, oppositely disposed welt engaging ribs 212, sole top engaging flanges 213, sole periphery engaging vertical rims 214, and the sole bottom engaging lip 215, in which are disposed the prongs 223 to 226 inclusive.

Further description of the prongs 223 to 226 is not considered necessary as they correspond in all respects to the prongs 23 to 26 described in connection with the first embodiment of the invention.

The tip protector 210 is of generally cup shape as best seen in Figures 13 to 15 inclusive, and affords a complete protection for the lower portion of the slipper 217. The protector is preferably made of metal and either decoratively treated as previously described, or covered with felt or leather when the sound of the protector striking the floor is to be avoided.

The attachment of the protector 210 upon the slipper 217 is accomplished by setting the toe portion 216 into the protector and forcing the prongs into the sole as best seen in Figure 15.

It may thus be seen that I have provided a novel shoe tip protector which may be made at low cost and yet which is light in weight, convenient, and useful. My shoe tip protector furnishes adequate protection for the shoe as well as the wearer's foot and yet is readily put in place or removed without the aid of special skill or tools. While the invention is especially useful in connection with children, to be worn while playing, or for adults, while engaged in hazardous occupations, or those in which the front portion of the shoe is subjected to a great deal of wear, it is obvious that any shoe in need of protection may be benefited by the use of my improved shoe tip protector.

As contrasted with certain constructions in the prior art, no interference is made with the shoe tip 16 and no pointed objects are inserted into the shoe at the welt, that is to say at the point of juncture between the upper and the sole, so that the water-proof, as well as the major foundation of the shoe is in no way interfered with.

I wish it to be understood that I do not desire to be limited to the exact details of construction shown and described for obvious modifications will occur to a person skilled in the art.

I claim:

1. A shoe tip protector comprising: a tip covering portion; a sole periphery engaging rim, associated with the lower part of the tip covering portion; and a plurality of prongs normally disposed outwardly of the inner wall of the said

sole periphery engaging rim and bendable inwardly through said rim to engage said sole edge.

2. For use with a shoe, a shoe tip protector comprising: a tip covering portion; a sole periphery engaging rim associated with the lower part of the tip covering portion; each of the lateral rear portions of the rim having a rear edge and having an incision forming a prong, said prong being disposed forwardly of the rear edge and being bendable about its connection to its respective lateral rim portion.

3. For use with a shoe, a shoe tip protector comprising: a tip covering portion; a sole periphery engaging rim associated with the lower part of the tip covering portion; each of the lateral rear portions of the rim having a rear edge and an incision having two ends, said incision forming a prong bendably connected to said rim and disposed forwardly of said rim rear edge, said prong having a first portion adjoining an imaginary line between said ends and a point portion connected to said first portion, said point portion being angularly disposed with relation to

said first portion, said prong being movable through the opening outlined by the incision which formed the prong, and whereby pressure upon the said first portion will force the point portion into the sole edge.

4. For use with a shoe, a shoe tip protector comprising: a tip covering portion; a sole periphery engaging rim associated with the lower part of the tip covering portion; each of the lateral rear portions of the rim having a rear edge and an incision having two ends, said incision forming a prong bendably connected to said rim and disposed forwardly of said rim rear edge, said prong having a first portion adjoining an imaginary line between said ends and a point portion connected to said first portion, said point portion being arcuately curved about said imaginary line as an axis, said prong being movable through the opening outlined by the incision which formed the prong, and whereby pressure upon the said first portion will force the point portion into the sole edge.

OSCAR J. CHERTOK.
